UNITED STATES PATENT OFFICE.

EDWARD J. FRITSCHE, OF NEW HAVEN, CONNECTICUT, ASSIGNOR OF ONE-HALF TO JULIUS TWISS, OF SAME PLACE.

GUIDING ATTACHMENT FOR SEWING-MACHINES.

SPECIFICATION forming part of Letters Patent No. 257,932, dated May 16, 1882.

Application filed January 9, 1882. (No model.)

To all whom it may concern:

Be it known that I, EDWARD J. FRITSCHE, of New Haven, in the county of New Haven, and in the State of Connecticut, have invented a new and useful Folding-Guide for Use with a Sewing-Machine; and I hereby declare the same to be fully described in the following specification and represented in the accompanying drawings, in which—

10 Figures 1 and 2 are perspective views, showing the larger and smaller ends of the scrolls of my improvement. Figs. 3 and 6 are plan views of the upper and lower scrolls, constructed of sheet metal. Fig. 4 is a plan view of a piece of sheet metal to which the scrolls are joined, and is itself attached to or forms part of the bed-plate. Fig. 5 is a plan view of the bed-plate, made of brass or other metal. Fig. 7 is a plan view of the scrolls as cut from sheet metal and before being bent. Fig. 8 is a perspective view of my improvement and of the cloth as it passes through it. Fig. 9 is a sectional view of the entire attachment with the several pieces of cloth in position.

25 Like letters refer to the same parts in the several figures.

The object of my invention is to fold the edges inwardly of two pieces or layers of cloth and guiding said folded edges one over the other, with the edge of a third piece or layer between them, and the whole being attached to a sewing-machine, so that the two folded edges and the piece between may be stitched together. Said pieces of cloth are not restricted in width, and each one may itself vary in width.

30 The folding parts of my device are constructed of or from a piece of sheet metal, as seen in Fig. 7, which is doubled, as shown in Figs. 3 and 6, so as to form tapering scrolls A a, while one end of said piece of sheet metal is elongated and curved, so as to form a smaller scroll, b, and gage for the end of the cloth.

The scrolls A a are fastened to the plate B, Fig. 4, by means of soldering or riveting, and plate B is itself fastened in the same manner to the bed-plate C. Plate B can also be made to form part of plate C. Plate B acts as a

support for the scrolls. C, Fig. 5, represents the bed-plate, in which D is the slot for the 50 reception of set-screw, whereby it is fastened to the table of a sewing-machine in the usual manner.

55 My invention is particularly useful in joining together the several pieces of cloth required in making corsets.

To use my improvement, place it flat upon the table of the sewing-machine, with the small end of the scrolls in front of the needle, and fasten down by set-screw passed through 60 slot D. Introduce the edges of the cloth to be folded in the larger end of the scrolls A a, drawing the same through until the needle is reached, and then introduce the piece to be joined in between the scrolls from the right 65 side. As the pieces of cloth are drawn through by the feed motion of the machine and leave the guide at f, Fig. 8, the edges are properly folded, and they, together with the intermediate piece, are in proper position for being 70 stitched together.

75 It will be observed that by means of my invention pieces already stitched together, but leaving their edges still separate, as in corsets, may be folded and stitched at the edges, no part of my improved device interfering with the operation.

What I claim as my invention is—

1. A folding guide and attachment for sewing-machines, composed of two separate exterior scrolls, A a, turning in reverse directions and united to and supported by an interior looped plate, B, attached to or forming part of the bed-plate C, substantially as and for the purpose described. 85

2. The combination of the two scrolls A a, the looper-plate B, to which they are united, and the plate C, by which the device is adjustably attached to the bed-plate of a sewing-machine, substantially as described. 90

In testimony whereof I have hereunto set my hand the 6th day of January, 1882.

EDWARD J. FRITSCHE.
